GUIDE CARD FOR CARD INDEXES

Filed March 8, 1923

Inventor.
Stanley Anthony
by Heard Smith & Tenant.
Atty.

UNITED STATES PATENT OFFICE.

STANLEY ANTHONY, OF BOSTON, MASSACHUSETTS.

GUIDE CARD FOR CARD INDEXES.

Application filed March 8, 1923. Serial No. 623,664.

To all whom it may concern:

Be it known that I, STANLEY ANTHONY, a citizen of the United States, and resident of Boston, county of Suffolk, State of Massachusetts, have invented an Improvement in Guide Cards for Card Indexes, of which the following description, in connection with the accompanying drawing, is a specification, like characters on the drawing representing like parts.

This invention relates to guide tabs for use in connection with guide cards for card indexes or for use in connection with book leaves, folders, etc. and it has for one of its objects to provide an improved guide tab which can be inexpensively made and which can be readily secured firmly to a card, leaf, sheet or folder.

The invention also has relation to guide cards for card indexes and another object of the invention is to provide an improved form of guide card which has a folded upper edge instead of a raw edge thereby not only stiffening the upper edge of the card but also providing an edge which will withstand the wear better than a raw edge.

Still another object of the invention is to provide an improved form of guide card having the above-mentioned features and in which the face of the card is smooth and free from shoulders with which the next adjacent card might engage as the cards are inserted or withdrawn.

A further object of the invention is to provide in strip form material for tabs adapted for use on guide cards, book leaves, folders, etc., which is so constructed that tabs of any desired length may be secured by merely cutting the required length from the strip and securing the tab in place.

A further object of the invention is to provide a guide card having a tab formed from a strip of sheet material doubled to provide a pocket for an index element and having its free extremities embedded in the substance of the card.

My improved guide card comprises a card body having at least two layers or plies at its upper portion and a guide tab having an anchoring portion extending therefrom which is located between the plies, said anchoring portion having openings or indentations and the plies being united through said openings or indentations. While this anchoring portion may

be made in various ways without departing from the invention I find it convenient to make it in the form of a plurality of anchoring arms which are spaced from each other and which are made with necked portions between their ends, the portions beyond the necks being wider than the necks. These anchoring arms are inserted between the plies of the card body and the latter are united on opposite sides of each necked portion of the anchoring arms, the wider lower end of each anchoring arm preventing it from being pulled out from between the plies. With this construction the anchoring arms are embedded in the substance of the card and also the plies of the card are connected together with a face-to-face contact immediately circumjacent the arms.

The body portion of the card is preferably formed with a folded upper edge and this may be secured either by folding a blank thereby to form said folded upper edge or by folding a strip of paper over said upper edge. In either case the folded upper edge, whether of the blank or of the strip, will be formed with one or more slots in the line of fold through which the anchoring members of the guide tab can be inserted so that the body of the guide tab will project beyond the folded edge while the anchoring members are confined between the two plies. This makes a very simple guide card which can be quickly and inexpensively manufactured and in which the guide tab is firmly and securely united to the card body.

It also forms a manner of securing tabs to the body which leaves the face of the body smooth and free from shoulders which are apt to be engaged by an adjacent card as the card is inserted or removed.

My invention also comprehends a tab member having openings along the edge thereof which overlies the edge of the card, sheet, leaf, etc., and an anchoring strip overlying the edge of the tab having the openings therein and the adjacent portion of the card or sheet, said anchoring strip being united to the card or sheet through said openings thereby anchoring the tab to the card or sheet.

In order to give an understanding of the invention I have illustrated in the drawings some embodiments thereof which will now be described after which the novel features

will be pointed out in the appended claims.

Fig. 1 of the drawings is a perspective view of a guide card embodying my invention;

5 Fig. 2 is an enlarged perspective view of the guide tab;

Fig. 3 is a fragmentary sectional view showing the anchoring members of the guide tab inserted through the slots in the card 10 but before the two portions of the card are adhesively united;

Fig. 4 is an enlarged sectional view on the line 4—4, Fig. 1;

15 Fig. 5 is an enlarged sectional view on the line 5—5, Fig. 1;

Fig. 6 is a view of a single ply card but having the folded edge;

Fig. 7 is a view showing a different embodiment of the invention;

20 Fig. 8 is a section on the line 8—8, Fig. 7;

Fig. 8^a is a section on the line x—x, Fig. 7;

Fig. 9 is a perspective view showing tab material in strip form;

25 Fig. 10 is a view showing a perforated strip to be used with the tab material for securing the tab in place.

As stated above one feature of my present invention relates to a guide card having a folded upper edge. In the drawings I have 30 illustrated a guide card at 1 and it is provided with the folded upper edge 2. This folded upper edge can be secured either by taking a sheet of paper twice the size of the card and then folding said paper centrally 35 to form the folded edge 2 and to form a card body having the two plies or layers 3 and 4 as shown in Fig. 1 or by making the card with an extension 5 which can be folded over against the body to form the 40 folded edge. A card which is made with the two plies 3 and 4 will have a body of double thickness. These plies will preferably be secured together in some suitable way, one 45 convenient way being by uniting them by means of some adhesive. An advantage of this method is that the two layers may be united throughout their entire extent.

If it is not desired to have the card of double thickness then the folded upper edge 50 2 may be obtained by taking a blank of the shape shown in Fig. 6 which has the body portion 1 of a size of the card 1 and is formed with the extension 5 which may be folded back on the body along the dotted 55 line 6 thereby forming the folded top edge 2 of the card, the flap or extension 5 being adhesively united to the body of the card.

Another way of providing a card having a 60 folded top edge is to take a card and fold a strip 14 over the edge as shown in Figs. 7 and 8^a, said strip being preferably adhesively united to the card.

The advantage of the card having the folded top edge 2 is that it stiffens the edge

and presents an edge which will wear much 65 better and give better service than a raw edge. In the use of card indexes the greatest wear on the cards comes on the top edges due to the constant picking over of the cards to find some particular card and where the 70 cards are provided with raw edges the top edges often become frayed or ragged. The folded edge 2 makes a more satisfactory card in many ways.

The guide tab is indicated generally at 7 75 and it is provided with an anchoring portion which is received between the plies at the top edge of the guide card. This anchoring portion will be provided with openings or indentations and the plies between 80 which the anchoring portion is situated are united firmly through the openings or indentations. Such openings or indentations may be provided for in a variety of ways, one of which would be to form the anchoring portion of the tab with the plurality of 85 separated arms or legs 8 thus leaving spaces 18 between them. These tabs may be made of any suitable material although some relatively stiff transparent material such as celluloid has many advantages.

If the guide tab is of that character having a pocket to receive a slip containing a 95 name or some other data then such guide tab can be conveniently made by folding a piece of celluloid back on itself and then forming the anchoring members 8 in one edge thereof. In thus folding the celluloid back on itself a pocket 9 between the two sides of the body of the tab may be formed which is open at each end and into which a slip of paper may be inserted bearing a name or any other desirable data, the latter being visible through the transparent celluloid.

100 As stated above the anchoring portion of each tab may conveniently be in the form of separated anchoring arms 8 and in the construction shown in Figs. 1 and 2 there are three such anchoring arms. Each anchoring arm is preferably given a necked shape so that it will be narrower at a point 10 between its ends than it is at its lower end as shown at 11, the portion 11 of each anchoring member forming a foot portion.

105 The guide card is formed with one or more slots 12 in the line of fold 6 and through which the anchoring arms 8 may be inserted as shown in Fig. 3, and after these anchoring arms have thus been inserted through the slots the plies between which the arms are received will be secured together through the openings 18 and immediately circumjacent each of the arms 8 with a face-to-face contact thereby firmly 110 anchoring the tab to the card. Where the card has the construction shown in Fig. 1 and is formed with the two plies 3 and 4 then the arms 8 will be inserted between 115 120 125

these two plies and they will be secured together by adhesive or otherwise through the openings 18.

Because of the necked construction of the arms the union of the two plies 3 and 4 at the points 15 each side of the neck 10 of the arms prevents the foot portion 11 of each arm from being pulled out from the card. Where the two plies 3 and 4 are united by some adhesive the union of the two plies at the points 15 on each side of the necks 10 may be accomplished by submitting the card to transverse pressure between two presser members, one of which should preferably be of soft resilient material so that it will conform more or less to the different thicknesses due to the pressure of the legs 8. The employment of such resilient presser members will force the two plies firmly together each side of the neck and in fact will cause a firm union of the portions of the plies immediately circumjacent each of the anchoring arms.

The assembling of the card and tab and the union of the two plies, therefore, involves simply inserting the anchoring arms 8 into the slots 12 and then uniting the two plies by some adhesive or otherwise so that they will become united closely circumjacent each anchoring arm 8.

In the construction shown the body portion of the tab 7 is inclined backwardly so as to make it easier to read the indicating slip which is inserted into the pocket 9.

Both faces of the card having the above construction are smooth and free from shoulders that are apt to engage or be engaged by the adjacent card when it is inserted or removed, this being the result of having the attaching portion of the tabs situated entirely between the two plies of the card.

There is another advantage resulting from the above construction and that is that by having the tab formed with a plurality of anchoring arms that are inserted through individual slots 12 the bridge portions 16 between the slots serve to tie the two plies together and prevent any danger of their being separated by a pulling strain on the tab 7.

When a card index is used and the cards are picked over it is the common practise for the operator to move the cards over by means of the tab and, therefore, each tab is continually subjected to a transverse pulling action. The use of the slots 12 and the intervening bridge portions 16 prevent any possibility of such pulling action separating the two plies at the point where the tab is secured.

Furthermore these bridge portions 16 act as stops to correctly position the tab when it is being assembled with the card. This operation of assembling the tab involves

merely inserting the arms 8 into the slots 12 as far as they will go or until the portions 17 of the tab engage the bridge portions 16 of the card. This ensures the proper position of the tab.

In Figs. 7 and 8 I have shown a different embodiment of the invention whereby the folded top edge of the card is secured by placing a binding strip along said edge. In this construction a reinforcing or binding strip 14 of paper or suitable material is folded over the top edge of the card 1 and adhesively united thereto thus producing the folded edge. The strip 14 is provided with the slots 12 to receive the arms 8 of the tab 7 and when the arms are inserted through the slots and then the binding strip 14 applied to the edge of the card and adhesively united thereto the tab will be firmly secured in place and the desired folded edge of the card will be produced.

Where this construction is employed and the tab is made of double thickness, as shown in Fig. 2, the edge of the card 1 may be inserted between the two sections of the legs 8 or the legs may be placed entirely on one face of the card. In either case when the strip 14 with its adhesive coating is secured in place said strip will be joined to the card through the openings 8 in the edge of the tab and thus the legs of the tab are situated between two plies which are united through the openings 18.

One advantage of this construction of tab is that it may be made in strip form as shown at 25 in Fig. 9 and tabs of different lengths may be provided by simply cutting the appropriate length from the strip. The strip will be provided in one edge with a plurality of equally-spaced openings or indentations 18 thus forming equally-spaced anchoring legs 8 and these anchoring legs will preferably be so shaped that they will be largest at the outer end. A strip of tab material having this construction can be cut into short lengths for the purpose of forming tabs for various purposes and each tab can be cut of a length suitable for the requirements of its use.

In connection with this strip tab material I propose to employ an anchoring strip for anchoring the tab to the card or sheet. One way of constructing this anchoring strip is shown in Fig. 10 wherein a strip 24 is provided with a row of slots 12 therein having the same spaced relation as the legs 8 of the tab strip 25. In using the tab material shown in Figs. 9 and 10 a length will be cut from the tab strip 25 suitable for use as a tab and then an appropriate length will be cut from the strip 24. The legs 8 of the tab are then inserted through the slots 12 in the strip 24 and the latter is then folded about the edge of the card or sheet and secured thereto preferably by means of some

suitable adhesive. This forms a tab having the construction illustrated in Figs. 7 and 8 and if the length cut from the strip 24 is long enough to extend the full length of the card 1 then a card with a folded edge will be provided.

While I have illustrated herein various forms of my invention I do not wish to be limited to the constructional features shown.

10 I claim.

1. A guide card for card indexes comprising a body having two layers at its upper portion and a guide tab having an anchoring arm situated between said layers, the latter being united with a face-to-face contact immediately circumjacent the anchoring arm.

2. A guide card comprising a body having two layers at its upper portion and a guide tab having a plurality of separated anchoring arms situated between the two layers, the latter being united with a face-to-face contact immediately circumjacent each arm.

25 3. A guide card comprising a body having two layers at its upper portion and a guide tab having anchoring arms situated between the two layers, said anchoring arms having a necked construction and the two layers being united with a face-to-face contact immediately circumjacent each arm.

30 4. A guide card comprising a body having two layers at its upper portion and a guide tab having a plurality of anchoring arms situated between the two layers, each arm having a necked portion intermediate its ends and a wider foot portion at its lower end and the two layers being united with a face-to-face contact immediately circumjacent each arm.

40 5. A guide card comprising a body having a folded top edge and formed with a slot in the line of fold and a guide tab having an anchoring portion inserted through said slot, the two sections being united immediately circumjacent the arm.

45 6. A guide card for card indexes comprising a body having two layers at its upper portion and a guide tab having an anchoring portion situated between said layers and formed with openings therein, the two layers being united in said openings with a face-to-face contact.

55 7. A guide card for a card index comprising a body having two layers at its upper portion and a guide tab having an anchoring portion situated entirely between said layers, said anchoring portion having openings through which the layers are united, each face of the card being free from shoulders.

60 8. A guide card comprising a body having a folded top edge and having a plurality of slots in the line of fold, and a guide tab having anchoring arms inserted through said slots, the two sections of the guide card

being united immediately circumjacent the arms and the portions of the card between the slots constituting positioning stops to engage the tab between the arms and thus position said tab.

70 9. Tab material for guide tabs comprising a strip of material folded lengthwise back on itself and having one edge formed with uniformly-spaced indentations thereby providing uniformly-spaced anchoring arms, each of which is provided with a neck portion and a foot portion at its end wider than the neck portion, whereby said strip may be cut into tabs of varying length.

75 10. Tab material for guide tabs comprising a strip of material folded back on itself longitudinally and having in one edge uniformly-spaced indentations thereby forming uniformly-spaced anchoring arms between indentations, each of which is widest at its outer end, and a strip of paper provided along its central line with perforations having the same spaced relation as the anchoring arms and of a size to receive said arms, whereby a tab of any desired length may be cut from the tab strip and a suitable length cut from the perforated strip and then the arms of the tab inserted through the perforations in the strip and the latter folded over the edge of a card or sheet and secured thereto.

80 11. The method of making a tab for a card, leaf or sheet comprising forming a tab strip having uniformly-spaced indentations on one edge thus producing uniformly-spaced anchoring arms, each of which is widest at its outer end, providing a strip having a row of perforations which have the same spaced relation as said arms and which are of a size to receive said arms, cutting from the tab strip a tab of the desired length, cutting a suitable length from the perforated strip, inserting the anchoring arms of the tab through the perforations in the severed perforated length, folding said perforated strip with its assembled tab over the edge of the card or sheet and uniting said perforated strip to said sheet.

85 12. A guide card for card indexes comprising a body having a plurality of layers at its upper portion and a guide tab extending beyond the edge of the card having an anchoring arm situated between certain of the layers, the latter being united with a face-to-face contact circumjacent said arm.

90 13. A guide card for card indexes comprising a body having a plurality of layers at its upper portion and a guide tab having an anchoring portion situated between said layers said anchoring portion having openings through which the layers are united with a face-to-face contact.

95 14. A guide card for card indexes com-

prising a body portion having a plurality of layers at its upper edge and a guide tab having an anchoring portion situated between certain of the layers, said anchoring portion having anchoring arms, each of which is wider at its end than at some intermediate point, the layers between which the arms are situated being united with a face-to-face contact immediately circumjacent each arm.

15. The combination with a card or sheet, of a guide tab having an anchoring portion which overlies the edge of the card or sheet and which has openings therein and an anchoring strip overlying the anchoring portion of the tab and united to the card through said openings.

16. The combination with a card or sheet, of a guide tab having an anchoring portion overlying the edge of said card and provided with openings and an adhesively-coated anchoring strip overlying the anchoring portion of the tab and the adjacent portion of the card or sheet and united thereto through said openings.

20. An index device comprising a card, and a tab formed from a strip of sheet ma-

terial doubled to provide a pocket for an index element and having its free extremities embedded in the substance of the card. 30

18. An index device comprising a card and a tab formed from sheet material doubled to bring its end portions into face-to-face contact, and to provide an open-ended index-receiving pocket at the fold, 35 said contacting end portions being disposed substantially in the plane of the main body of the card and concealed within the thickness of the latter.

19. An index device comprising a card 40 having separated plies at one edge, and a tab consisting of a strip of thin sheet celluloid bent intermediate its ends to form an open-ended pocket for the reception of an index slip and to bring its end portions 45 into face-to-face contact with each other to form attaching means, said attaching means being disposed between the plies of the card, and means for securing the attaching means and the respective plies in assembled relation. 50

In testimony whereof, I have signed my name to this specification.

STANLEY ANTHONY.
